UNITED STATES PATENT OFFICE

MACLYN GUHL, OF NEW YORK, N. Y., ASSIGNOR TO MOSS-STILL, INC., OF NEW YORK,
N. Y., A CORPORATION OF NEW YORK

DESIGN FOR A TEXTILE FABRIC

Application filed November 3, 1932. Serial No. 45,717. Term of patent 3½ years.

To all whom it may concern:

Be it known that I, MACLYN GUHL, a citizen of the United States, residing at the city of New York, in the county of New York, State of New York, have invented a new, original, and ornamental Design for a Textile Fabric, of which the following is a specification, reference being had to the accompanying drawing, forming part thereof,

The figure is a plan view of a textile fabric, showing my new design. A single unit of my design is substantially comprised within the area defined by the indicating lines shown on the drawing.

I claim:

The ornamental design for a textile fabric, substantially as shown and described.

MACLYN GUHL.
